UNITED STATES PATENT OFFICE.

WILLIAM C. SCHRAMM, OF BARTON, MARYLAND.

CURTAIN-FIXTURE.

SPECIFICATION forming part of Letters Patent No. 625,422, dated May 23, 1899.

Application filed February 24, 1899. Serial No. 706,733. (No model.)

To all whom it may concern:

Be it known that I, WILLIAM C. SCHRAMM, a citizen of the United States, residing at Barton, in the county of Allegany and State of Maryland, have invented certain new and useful Improvements in Curtain-Fixtures; and I do declare the following to be a full, clear, and exact description of the invention, such as will enable others skilled in the art to which it app pertains to make and use the same.

My invention relates to certain novel improvements in combined curtain-pole and window-shade fixtures; and the object is to provide a simple, inexpensive, convenient, and effective device of this character.

With this object in view the invention consists in certain features of construction and combination of parts, which will be hereinafter more fully described and claimed.

In the accompanying drawings, Figure 1 is a perspective view of a combined curtain-pole and shade fixture embodying my invention. Fig. 2 is a horizontal section through the adjustable base-boards. Fig. 3 is a transverse section through the line 3-3 of Fig. 2.

1 and 2 represent the base-boards, the meeting ends of which are formed with parallel tongues 1' and 2' lying in the same plane and having a sliding engagement with each other, 30 the tongue 1' carrying a clip 3, which extends downward across the face of the two tongues, its lower end 3' being turned inwardly to engage the longitudinal slot 2² in the tongue 2', and its rear end 3² is turned downwardly to prevent the clip becoming detached from the tongue. A similar clip 4 is fixed in the tongue 2', and its upper end 4' passes through a slot 1² in the tongue 1', and its end 1³ turned upward, as in the first instance. This construction permits the base-boards to be adjusted with reference to each other, so as to conform to the width of the window-frame, and when so adjusted the thumb-screws *a a* may be tightened up to secure the base-boards in their 45 adjusted position.

Near the outer end of the base-board 1 is formed a groove or recess 5, one of the walls 5' of which is right angular, and the opposite wall 5² is dovetailed to receive the dovetailed 50 edge 6² of the body portion 6' of the shade-bracket 6, and a corresponding groove or recess 7 is formed in the base-board 2. One of

the walls 7' is formed at a right angle to the face of the board, and the other wall 7² is dovetailed to receive the correspondingly- 55 formed edge 8² of the body portion 8' of the shade-bracket 8.

The bracket 8 is formed with an ear 8³, provided with an orifice 8⁴ to receive the cylindrical journal of the usual self-acting shade-roller, and the corresponding bracket 6 is formed with a similar ear 6³, having the usual rectangular notch 6⁴ to receive the rectangular end of the spring-actuated shaft of the shade-roller. 65

The upper horizontal edges of the brackets 6 and 8 are each provided with a rectangular notch 9 to receive the rectangular ends 10 10 of the bowed curtain-pole 12, the free ends of which terminate in the ornamental end pieces 70 13 13.

In suspending the curtain from the bowed curtain-pole the curtain is held away from the shade and a greater artistic effect is produced in the display of the curtain. 75

In inserting the brackets in their respective grooves the beveled or dovetail edge is first inserted in the groove and the bracket proper turned at a right angle to the base-board and the curtain-pole then placed in the 80 brackets, thus effectively securing them in place.

The accompanying drawings show my invention in the best form now known to me; but many changes in the details might be 85 made within the skill of a good mechanic without departing from the spirit of my invention as set forth in the claims at the end of this specification.

Having thus fully described my invention, 90 what I claim as new and useful, and desire to secure by Letters Patent of the United States, is—

1. The adjustable base-boards, provided with the vertical parallel grooves, each of 95 which is formed with a right-angular and a parallel undercut wall, the brackets mounted in said grooves and provided with correspondingly-formed ears, and having a rectangular notch formed in their upper edges, and a curtain-pole formed with rectangular ends to engage said notched brackets, substantially as described. 100

2. The base-boards 1 and 2, formed with

the parallel tongues 1' and 2' which are provided with the slots 1², 2² the clips 3 and 4 fixed to the tongues 1' and 2', respectively, and having a sliding engagement with said slots, and means carried by the clips for locking them in their adjusted position, substantially as and for the purpose set forth.

In testimony whereof I have hereunto set my hand in presence of two subscribing witnesses.

WILLIAM C. SCHRAMM.
